LEO ROSEMAN, OF NEWARK, NEW JERSEY

HOOK-TAPE-SEWING MACHINE

Application filed June 1, 1928. Serial No. 282,113.

This invention relates, generally, to improvements in sewing machines; and the same has reference, more particularly, to a novel construction of machine especially adapted for stitching hook-fastener tape to garments and the like.

The invention has for its principal object to provide a novel hook-tape guiding and control means which is adapted to keep the hook-tape perfectly aligned to the sewing needle or needles as it moves under the impulsion of the normal feed devices of the stitching mechanism past the sewing point, to the end that close and accurate placing of the line of stitches relative to the hooks of the tape may be attained without distorting or displacing strains being imposed on the tape at the sewing point, and so that rapid stitching may be carried on without danger of the metallic hooks of the tape coming in contact with the sewing needle or needles with consequent risk of either breaking the needle or damaging the hook fasteners.

Other objects of this invention, not at this time more particularly enumerated, will be clearly understood from the following detailed description of the same.

This invention is clearly illustrated in the accompanying drawings, in which:

Fig. 1 is a front side elevation of a sewing machine for sewing hook-tape according to this invention; Fig. 2 is an end elevation of the same in part section; Fig. 3 is a fragmentary sectional view, taken on line 3—3 in Fig. 2 but drawn on an enlarged scale; Fig. 4 is an enlarged detail plan view of the hook tape guiding and control rollers on an enlarged scale; Fig. 5 is a side elevation of a modified form of hook-tape guiding and control roller; and Fig. 6 is a sectional view of the latter, taken on line 6—6 in Fig. 5.

Similar characters of reference are employed in all of the hereinabove described views, to indicate corresponding parts.

Referring to said drawings, the reference character 10 indicates the bed-plate of the sewing machine, upon which is mounted the arm 11, at the free end of which is arranged the usual reciprocating needle bar 12 and spring tensioned presser foot 13, the same be-

ing actuated from the main shaft 14, which extends through the arm 11 in the usual way. Connected with the bed-plate 10, so as to lie beneath the sewing point of the machine and thus extend beneath the presser foot 13 is a 55 throat plate 15. Said throat plate 15 is provided with elongated laterally spaced openings 16 beneath the presser foot 13. Cooperating with said presser foot 13 is the feed-dog 17 which is provided with laterally spaced 60 serrated jaws 18 which extend upwardly through the openings 16 of the throat plate 15 so as to operatively engage and feed the work passing the sewing point intermediate the presser foot and throat plate. Said feed-dog jaws 18 are provided with perforations 19 through which the needles 12' of the sewing mechanism may extend on their descending movement. Preferably the needle bar arrangement is of the oscillating or rocking 65 type, whereby when the needles enter the feed dog jaws the same will swing forward synchronously with the forward work feeding movement of the feed dog. I have illustrated in the drawings a two-needle type sewing 70 mechanism, and the throat plate is provided with a longitudinal clearance channel 20 extending beneath the presser foot 13 and intermediate the jaws of the feed dog 17, the same being of sufficient depth to provide a 75 clearance space through which the hooks h of the tape t may pass as the tape (hook-side down), together with the garment body to which it is to be stitched, rides over the surface of the throat plate and between the 80 presser foot and feed-dog jaws during the sewing operation, thus assuring that the metallic hook-bills will not be crushed or distorted during the sewing operation. It will be obvious that, one of the needles may be 85 omitted, if it is desired to utilize the machine as a single needle machine. It will also be obvious, should it be desired to feed and sew the hook tape with the hook-side up, that the clearance channel 20 may be reversed in respect to the cooperative relation of throat plate and presser foot, i. e. such channel 20 may be omitted from the throat plate and provided in the bottom of the presser foot, 90 such change being, to those skilled in the art, 95 100

an obvious equivalent for that above described and shown in the drawings.

The means for guiding and controlling the movement of the hook-tape to the sewing mechanism of the machine, so that the same will travel true and straight without distortion or such accidental displacement as might be likely to permit some portion of the metallic hooks to be engaged by the sewing needles with risk of injury to either the one or the other, comprises, in one exemplifying form, the following structure:—

Journalled in and between an upper bearing 21 (which is fixed on the machine arm 15 11) and a lower bearing 22 (mounted on the bed-plate 10) is a vertical shaft 23. This shaft 23 is driven from the main shaft 14 of the machine by means of an intermeshing worm 24 and worm gear 25 respectively fixed 20 on said main shaft 14 and vertical shaft 23. Mounted in bearings 26 adjacent to said vertical shaft 23 is a transverse shaft 27, the same being driven from said vertical shaft by means of intermeshing screw gears 28 and 25 29 respectively fixed on said vertical and transverse shafts. Fixed on said bed-plate 10, so as to overhang the front side thereof, is a bearing bracket 30. Journalled in said bearing bracket is a lay shaft 31. This lay 30 shaft 31 is driven from said transverse shaft 27 by means of intermeshing screw gears 32 and 33 respectively fixed on said transverse and lay shafts. Fixed on the outer end of said lay shaft 31, so as to be rotated thereby 35 is a tape guiding and control roller 34, the same having an annular channel 35 in its circumferential face to accommodate the projecting parts of the metallic hook fasteners carried by the tape. At its forward end said bearing bracket 30 possesses a depending arm 36, and journalled on a stud 37 carried by said depending arm is an idler guide roller 38 vertically aligned relative to said tape guiding and control roller 34. Said bearing bracket 40 45 30 is further provided with a guide plate 39 disposed intermediate the rollers 34 and 38 and in vertical plane tangent to the tape supporting surfaces thereof, said guide plate also having a channel 40 in its face to accommodate the projecting parts of the metallic hook fasteners carried by the tape. Projecting forwardly from the lower end of said bearing bracket arm 36 is a knuckle 41, and pivotally connected thereto by a fulcrum 50 55 stud 42 is an upwardly extending bearing arm 43. Journalled in the upper end of said bearing arm 43 is a spindle 44, and fixed on the outer end of said spindle is a gripping roller 45 to cooperate with said tape guiding and control roller 34. Said gripping roller 45 is driven in an opposite direction to the tape guiding and control roller 34 by means of intermeshing spur gears 46 and 47 respectively fixed on said lay shaft 31 and spindle 60 65 44. The bearing arm 43 is yieldably pressed

inwardly to tensionally press said gripping roller 45 into gripping relation to the tape passing over the tape guiding and control roller 34; and to this end suitable pressure spring means 48 is provided. The rollers 34 and 35 may be separated for the insertion of the tape therebetween, and for this purpose the bearing arm 43 is provided, at its upper end, with a nosing 49 engageable by the cam member 50 of a pivoted lever 51, so that by swinging upwardly said lever 51 the cam member 50 presses outwardly on said nosing 49 to thereby swing outward the bearing arm 43 against the tension of the spring 48.

Connected with said bearing bracket 30 is a slideway 52 in which is slidably movable a stop bar 53 which may be projected into the path of movement of the tape *t* over the guide plate 39 so as to engage the hook fasteners of the tape in such manner as to arrest the tape when necessary to prevent over-running of the same to the sewing point. Said stop-bar is intermittently actuated in timed relation to the work feeding operations of the sewing mechanism as follows:—

Pivoted on said bearing bracket 30 is an oscillatable lever 54 the upper end of which is provided with a roller or stud 55 engageable by an actuating cam 56 mounted on and rotated by said transverse shaft 27, and to the lower arm of which is pivotally connected the rear end of said stop bar. A pull spring 57 is interconnected between a stationary anchor post 58 and the lower arm of said lever 54 to normally project the stop bar forward to operative position, the latter being intermittently retracted by the action of the cam 56. Should it be desired to hold the stop-bar inactive, a check-pawl 59 is pivoted to the bearing bracket 30, and the stop-bar is provided with a notch 60, so that by drawing back the stop-bar, slightly beyond its normal rearward stroke, the check-pawl may engage said notch so as to hold said stop-bar immovable until again released.

In operation, the hook tape is led from a supply reel (not shown) over the guide roller 38 and then upwardly over the guide plate 39 to pass between the roller 34 and 45 and thence forwardly so as to traverse the throat plate 15 to the sewing point, at which point it is engaged by and between the presser foot 13 and feed-dog 17 so as to be propelled forward thereby (together with the garment body which is fed through the hemmer *H* to pass with the tape to the sewing point) in such manner as to produce the desired stitching. The rollers 34 and 35 relieve the presser foot-feed dog mechanism from the drag of the tape, while nevertheless keeping the latter straight and accurately aligned to the sewing needles as well as perfectly controlled against over or under feeding. The channels 35 of the roller 34 and 20 of the throat plate 15 accommodate the projecting portions of 130

the hooks of the tape so that the latter lies flat and smooth at all times during its progress to and through the sewing mechanism, while at the same time fully protecting the 5 projecting portions of the hooks against being crushed or otherwise distorted. It will be obvious, that the tape *t*, as thus guided and controlled, is held against side slipping or other displacement likely to prevent the accurate placing of the stitches, or likely to 10 carry the metallic fasteners of the tape in contact with the sewing needles; and by reason of such guiding and control it is possible in the operation of the machine of this invention to form the lines of stitches very close 15 to the edges of the tape without danger of running off the same, thus enabling machine stitching to be rapidly produced along very narrow and restricted tape margins. This is 20 possible even when applying tape to curved garment edges, due to the perfect control of the tape as it passes to the sewing point.

Referring now to Figs. 5 and 6 I have shown a modified form of guiding and control roller, the use of which will permit the gripping roller 45 to be dispensed with. This modified roller is provided on its circumferential face with equi-spaced flattened bearing faces or facets 61 to engage the tape 25 body *t*, each face or facet having an indented pocket 62 to receive the projecting portion of the hook fasteners *h*. The angular relations of the faces or facets 61 together with the pockets 62 serve to grip the tape sufficiently 30 to assure both its forward movement as well as its timed control; all of which will be understood from an inspection of the said Figs. 35 5 and 6 of the drawings.

I am aware that various changes may be 40 made in the general arrangements and combinations of the several devices and parts, as well as in the details of the construction of the same, without departing from the scope of this invention as described in the foregoing 45 specifications, and as defined in the appended claims. Hence, I do not limit this invention to the exact arrangements and combinations of the various devices and parts as set forth in the foregoing specification, nor do I confine 50 myself to the exact details of the construction of said parts as illustrated in the accompanying drawings.

I claim:—

1. In a sewing machine having a stitch-spacing feed including a channeled throat- 55 plate, presser foot and feed dog, and a stitch-forming needle mechanism; means to guide and control the movement of hook-tape to said stitch-spacing feed and needle mechanism comprising, a guiding and control roller in advance of said stitch-spacing feed and needle mechanism, said roller having an annular channel to accommodate the projecting hook portions of the tape, said roller 60 channel being aligned with the throat-plate

channel; a tape gripping roller cooperating with said guiding and control roller, and transmission means actuated from the main shaft of the sewing machine to operate said guiding and control roller and cooperating 70 gripping roller in timed relation to the operation of said stitch-spacing feed.

2. In a sewing machine for sewing hook tape, a stitch-spacing feed including a throat-plate, a presser foot and feed dog; said throat-plate having a clearance channel extending therethrough beneath the presser foot and intermediate the jaws of the feed dog adapted to receive the projecting portions of the hooks of the tape; a pair of rotated tape 80 gripping rollers in advance of said throat-plate between which the tape passes so as to be engaged and fed forward thereby toward the stitch-spacing feed, one of said rollers having an annular channel in its operative face to receive the projecting portions of the hooks of the tape; said channels of said throat-plate and roller being disposed in aligned relation one to the other, and means 85 to actuate said rollers in synchronized relation to the operation of said stitch-spacing feed.

3. In a sewing machine for sewing hook tape, a stitch-spacing feed including a throat-plate, a presser foot and feed dog; said throat-plate having a clearance channel extending therethrough beneath the presser foot and intermediate the jaws of the feed dog adapted to receive the projecting portions of the hooks of the tape; a pair of rotated tape gripping rollers in advance of said throat-plate between which the tape passes so as to be engaged and fed forward thereby toward the stitch-spacing feed, one of said rollers having an annular channel in its operative face to receive the projecting portions of the hooks of the tape; said channels of said throat-plate and roller being disposed in aligned relation one to the other, and means to govern the movement of said tape for controlled advance through and by said gripping rollers. 95

4. In a sewing machine for sewing hook tape, a stitch-spacing feed including a throat-plate, a presser foot and feed dog; said throat-plate having a clearance channel extending therethrough beneath the presser foot and intermediate the jaws of the feed dog adapted to receive the projecting portions of the hooks of the tape; a pair of rotated tape gripping rollers in advance of said throat-plate between which the tape passes so as to be engaged and fed forward thereby toward the stitch-spacing feed, one of said rollers having an annular channel in its operative face to receive the projecting portions of the hooks of the tape; said channels of said throat-plate and roller being disposed in aligned relation one to the other, means to actuate said rollers in synchronized relation to the operation of said stitch-spacing feed, and means to govern 100

the movement of said tape for controlled advance through and by said gripping rollers.

5. In a sewing machine having stitch-spacing feed including a channeled throat plate, a presser foot and feed dog, means to guide and control the movement of hook tape to said stitch-spacing feed comprising, a roller in advance of the stitch-spacing feed having hook-receiving space in the periphery thereof, said roller being positioned relative to said channeled throat-plate so that the hook-receiving space of the same is in line with the channel of the latter.

In testimony, that I claim the invention set forth above I have hereunto set my hand this 31st day of May, 1928.

LEO ROSEMAN.
